GAME BALL TRACK BOARD

Jerome D. Enoch, Bronx, N.Y., assignor to Jaymar
Specialty Company, Brooklyn, N.Y., a partnership

Filed May 20, 1964, Ser. No. 30,081

Term of patent 14 years

(Cl. D34—5)

FIG.1

FIG.5

FIG. 1 is a perspective view of a game ball track board showing my design;

FIG. 2 is an end view drawn to larger scale and looking toward the lower end as seen in FIG. 1;

FIG. 3 is an end view drawn to larger scale and looking toward the upper end as seen in FIG. 1;

FIG. 4 is side elevation; and

FIG. 5 is a bottom view of the same.

I claim:

The ornamental design for a game ball track board, substantially as shown.
